UNITED STATES PATENT OFFICE.

EBER CHARLES AUSTIN, OF WAHOO, NEBRASKA.

VALVE-SPRING LIFTER.

1,349,934.

Specification of Letters Patent. Patented Aug. 17, 1920.

Application filed May 29, 1919. Serial No. 300,656.

To all whom it may concern:

Be it known that I, EBER CHARLES AUSTIN, a citizen of the United States, residing at Wahoo, in the county of Saunders and State of Nebraska, have invented certain new and useful Improvements in Valve-Spring Lifters, of which the following is a specification.

The object of this invention is to provide a simple, inexpensive and easily operated tool by the use of which the work of assembling or disassembling the parts of a valve in an internal combustion engine will be expedited. The invention is illustrated in the accompanying drawings and will be hereinafter fully described, the novel features being subsequently pointed out in the appended claims.

In the drawings—

Fig. 1 is a perspective view of my improved tool;

Fig. 2 is an edge elevation of the upper portion of the tool;

Fig. 3 is a side elevation of the tool showing the manner of applying the same;

Fig. 4 is a view showing the body and the presser pivot or pin in section;

Fig. 5 is a horizontal section on the line 5—5 of Fig. 3;

Fig. 6 is a detail plan view of the foot;

Fig. 7 is an elevation of another form of the invention;

Fig. 8 is a perspective view of the upper portion of the tool shown in Fig. 7.

In carrying out my invention, I employ a standard or supporting bar 1 which is provided with a lateral foot 2 adapted to engage around the stem of the valve and under the spring cap or collar thereon, the extremity 40 of the foot being forked, as shown at 3, to facilitate such engagement. The standard is preferably constructed of two similar metallic bars welded or otherwise firmly secured together and having their lateral

45 portions free of each other but normally lying close together, the fork 3 being formed by offsetting the extremities of the lateral foot members 2, as clearly shown. A set bolt 4 is mounted transversely in the foot members, as shown, and the fork may be adjusted to accommodate valve stems of different diameters by manipulating the said bolt 4 in an obvious manner. Slidably fitted upon the standard 1 is a body 5 which is preferably constructed of a blank of sheet steel

doubled upon itself into substantially inverted U-shape and provided in its shoulder portion at one end with a recess or notch, as shown at 6, to fit around the standard. Between the wings or side members of the body, 60 I place blocks 7 which are adapted to fit against the opposite edges of the standard, as shown most clearly in Figs. 4 and 5, and thereby serve as guides to maintain the proper relative position of the body upon 65 the standard during the adjustment and operation of the device. These blocks are secured permanently in position by rivets or similar fastenings 8 inserted through the sides of the body 5 and the ends of the 70 blocks as will be readily understood. The lower edges of the body 5 are cut-away toward their free ends, as shown at 9, to accommodate the movement of a pivot 10 and a spacing pin 11 which are secured to and 75 extend between the links 12 which are pivoted at their rear ends to the hand lever 13. The pivotal connection, 14, of the links and the said hand lever is disposed near the fulcrum of the lever which is inserted through 80 the lever and lugs or ears 15 projecting from the body 5. The lever 13 is preferably constructed by rolling a block of sheet steel into the desired form so that the dead weight of the tool will be minimized. The pivot 10 85 at the front ends of the links 12 forms the pivotal connection between the members 16 and 17 of a toggle, the members 16 having their upper ends pivoted, as shown at 18, between the sides of the body 5 at the free 90 end thereof and the member 17 being disposed between the lower ends of said members 16 and mounted upon the pivot 10. The lower end of the toggle member 17 is pivoted between the sides of a U-shaped arm 95 19 which is fulcrumed, as at 20, between the sides of the body 5 at the lower edge thereof and carries at its forward free end a presser pin 21 which is adapted to engage the body 22 of the valve. The pin 21 is secured 100 rigidly at its upper end between the sides of the arm 19 and the free extremities of said sides are bent toward each other, as shown at 23, so as to effect a firm engagement with the pin and prevent twisting of 105 the same.

The use of the device will, it is thought, be readily understood on reference to Fig. 3. When it is desired to remove a valve from a motor, indicated conventionally at 24, the 110

fork 3 is engaged under the spring cap or collar 25 with the handle 13 raised, as shown in Fig. 4, in which position the toggle will be collapsed and the presser pin 21 relatively raised. The tool is then rocked about the point of engagement between the fork 3 and the valve stem 26 so as to bring the presser pin 21 into position over and bearing upon the valve body 22, after which the handle 13 is swung downwardly to the position shown in Fig. 3 which movement will cause the pin 21 to serve as a pivot or fulcrum upon which the body 5 and standard 1 will be caused to rise thereby compressing the spring 27 and lifting the collar or cap 25 so that the cotter pin or other retaining device 28 may be removed. The toggle will be straightened and will thereby serve to lock the tool upon the valve so that the spring will be held under compression until the retaining devices are removed, after which the tool may be released and the valve withdrawn for cleaning or whatever repairs may be needed. The same operation may be followed to permit the easy assembling of the different parts of a valve with the motor and the work involved in fitting a valve in place or cleaning the same or any of the parts adjacent thereto is thereby facilitated and time saved.

My device is exceedingly simple in the construction and arrangement of its parts and is very effective when in use. The body 5 may be moved along the standard 1, so as to accommodate the tool to valve stems of different lengths, and when it has been brought to the desired position upon the standard it may be secured in that position by a set screw or bolt 29 mounted in the upper end of the outer block 7 and bearing against the standard as will be readily understood. The standard 1, the pin 21 and the toggle member 17 are illustrated as constructed from solid bodies of metal but all the other parts of the device may be constructed from pressed sheet steel so that the tool will possess sufficient strength to withstand all strains to which it is subjected without being so cumbersome or heavy that it may not be easily handled. I prefer to employ bar metal for the standard and the presser pin 21, but the toggle member 17 may be of sheet material if so desired. The blocks 7 are also shown as being of bar material but they may be of sheet metal or of other light construction without detracting from the usefulness or any of the advantages of the tool. A link 12 is disposed at each side of the body 5 so that the pull upon the toggle will be balanced and the spacer 11, interposed between the said links, counteracts any tendency of the same to bend at points between the toggle and the edge of the body.

65 In Figs. 7 and 8 I have shown a somewhat

simpler form of the invention which is particularly adapted for use in shops handling motors of a single type and all of the same dimensions. In this embodiment the adjustable body is omitted and the upper end 70 of the standard 30 is provided with an integral lateral arm 31 to the extremity of which the upper toggle members 32 are pivoted. The arm 33 is pivoted to the standard, as at 34, but is otherwise the same in 75 all respects as the arm 19 in the previously described form. The presser pin 35 is identical with the pin 21 and the lower toggle member 36 connects the arm 33 with the upper toggle members. The handle or operating lever 37 is fulcrumed, as at 38, to an ear or lug 39 on the standard and is connected by links 40 with the pivot joint of the toggle.

Having thus described the invention, 85 what is claimed as new is:

1. In a tool for the purpose set forth, the combination of a standard, a body extending laterally from the standard, an arm pivoted to the body, a presser pin carried by 90 the free end of said arm, toggle members pivoted to the body and the said arm, respectively, and pivotally connected to each other, links extending from the pivotal connection between the toggle members, and a hand lever fulcrumed upon the body and pivoted to said links.

2. A tool for the purpose set forth comprising a standard, a body mounted on and extending laterally from the standard, a fork at one end of the standard, a presser pin carried by the free end of the body, and toggle mechanism mounted upon the body and connected with the presser pin to move the same into or out of engagement with the 105 valve and lock it in the engaged position.

3. A tool for the purpose set forth comprising a standard having a foot at one end, a laterally extending body mounted on and adjustable longitudinally of the standard, 110 an arm pivoted to and extending beyond the body, a presser pin carried by the free end of said arm, toggle mechanism connecting the body and said arm, and means mounted on the standard and connected with the toggle mechanism to effect movement of the arm toward or from the foot.

4. In a tool for the purpose set forth, the combination of a standard, a body mounted on and adjustable longitudinally of the 120 standard, an arm pivoted to the body, a presser pin carried by the free end of said arm, toggle members pivoted to the body and the said arm, respectively, and pivotally connected to each other, links extending from the pivotal connection between the toggle members, and a hand lever fulcrumed upon the body and pivoted to said links.

5. A tool for the purpose set forth com- 130

prising a standard having a foot at one end, a body comprising a sheet pressed into inverted U-form and having its side members passing at opposite sides of the standard, 5 blocks secured between the sides of said body and bearing against the opposite edges of the standard, an arm pivoted to the body,

a presser pin carried by the said arm, toggle mechanism carried by the body and said arm for swinging the arm, and means 10 mounted in one of the blocks to secure the body in a set position on the standard.

In testimony whereof I affix my signature.
EBER CHARLES AUSTIN. [L. s.]
